SPINNING TOY OR THE LIKE

Joan L. Oliver, 8 Montego Key,
Novato, Calif. 94947

Filed Oct. 15, 1969, Ser. No. 19,573

Term of patent 14 years

Int. Cl. D21—02

U.S. Cl. D34—15

Fig. 1.

Fig. 2.

Fig. 3.

FIG. 1 is a side elevation of a spinning toy or the like showing my new design.

FIG. 2 is a top plan view. The bottom plan view is identical.

FIG. 3 is an end elevation. The end elevation taken from the other end is identical.

I claim:

The ornamental design for a spinning toy or the like, as shown and described.
